KITE

Fred H. Ohland, Gibbon, Minn.

Application May 28, 1949, Serial No. 96,079

2 Claims. (Cl. 244—153)

1

This invention relates to improvements in kites.

It is an object of the invention to provide a kite construction which is simple and cheap to manufacture and which at the same time is sturdily constructed, so that it will withstand relatively high winds and will greatly resist breakage in the event it should dive to the ground.

Another object of the invention is to provide a kite construction which is supplied with a bridle cord or cords so arranged that the lead cord or cords will be connected thereto with the bridle cord held at the proper angle to the surface of the kite.

Another object of the invention is to provide a kite with simple but efficient means for steering the same, and for reeling and unreeling the lead cord.

The above and other objects and advantages of the invention will more fully appear from the following description made in connection with the accompanying drawings, wherein like reference characters refer to the same parts throughout the views, and, in which:

Fig. 1 is a perspective view of the embodiment of the invention showing the kite and control and winding reel in operative positions.

Fig. 2 is a plan view of the kite.

Fig. 3 is a side elevational view.

Fig. 4 is an end view.

Fig. 5 is a perspective view of the kite showing one form of bridle and lead cord tying means.

Fig. 6 is an enlarged fragmentary detail of the tying means shown in Fig. 5.

Fig. 7 is an enlarged fragmentary perspective of the cover sheet securing means.

Fig. 8 is a view similar to Fig. 7 with a portion of the cover sheet disconnected from the frame.

Fig. 9 is an enlarged plan view of another form of bridle and lead cord tying means, the cords being shown in dotted lines, and

Fig. 10 is an enlarged longitudinal sectional view through the control and winding drum.

The kite has a frame including an upright 11 and a cross-member 12, these being suitably connected as by a small brad 13.

Fig. 7 shows one end of the cross-member 13 and it is provided with a notch or slot 14 cut in from its end. This notch is preferably formed on each end of the upright and the cross-piece.

The kite has a cover sheet 15 which ordinarily is of paper or of other suitable material. The cover sheet is generally of polygonal shape and its edges having reinforcing strips 16 secured

2

thereto in any suitable manner, such as by an adhesive. At each corner of the cover sheet 15 the edge reinforcing strips 16 overlap as shown in Figs. 7 and 8, and an aperture 17 is formed through this reinforced and overlapped corner.

The apertures 17 in the corners of the cover sheet and the reinforcing strips are adapted to receive a rubber binder 18 therethrough, as indicated in Fig. 8, leaving a loop 19 at each side

10 of the sheet 15. These loops are placed in the notches 14 and in the ends of the frame pieces, as shown in Fig. 7, so that the cover sheet 15 is resiliently connected to the ends of the upright 11 and the cross-piece 12. Thus the sheet

15 is stretched fairly tightly over the frame, yet it will give when the kite hits the ground or some other solid object, and it has been found that it will stand considerable shock without rupturing the coversheet.

10 The kite is shown with a pair of bridle cords 20 secured at spaced points to the cross-piece 12, and a complementary pair of bridle cords 21 extending from a lower portion of the upright 11 and diverging upwardly and outwardly and connected with the outer ends of the bridle cords

25 as shown in the drawing and extend downwardly to a reel construction to be described below.

10 In Fig. 6 one form of bridle cord and lead cord tie arrangement is shown. The bridle cords 20 and 21 are provided with pre-formed and permanent loops 23 and 24 respectively. The upper end of a lead cord is extended through said loops

35 and tied to form a loop 25. The loops 23 and 24 are formed by the kite-maker on the bridle cords 20 and 21 so that when the lead cord 22 connects them together there will be a definite angle of the bridle cords 20 relative to the general plane of the cover sheet 15. As best shown

40 in Fig. 3, the bridle cords 20 lie at right angles to the general plane of the kite and its cover sheet.

10 In Fig. 9 there is shown another form of tie means for the bridle cords and lead cords. This is a wire element 26 having a split loop 27 to which the lead cord 22 is tied. The other end of the tie element 26 is provided with a keyhole loop 28, which is adapted to receive the knotted ends of the bridle cords 20 and 21. It is preferred

50 that the bridle cords 20 and 21 be knotted at the factory in order to maintain the desired angular relationship mentioned in the preceding paragraph.

10 In Fig. 10 there is shown a reel 29 made up of cylindrical sections 30 having closed adjacent

end portions 31 pivotally connected by a bolt 32 having a wing nut 33 thereon. One of the sections 30 can be rotated relative to the other and it is preferred that the wing nut 33 be tightened to the extent that the two sections 30 will have a dragging frictional contact between them, so that normally they will turn together but one can be held stationary while the other is rotated or partially rotated.

Each of the cylindrical drum or reel sections 30 has a pair of flanges 34 thereon and about its cylindrical wall. These flanges 34 are spaced inwardly from the outer ends of the sections 30 and the flanges of each pair are spaced from each other, so that there is a reel hub section 35 between each of the flanges of a pair. It should also be noted that the flanges of each pair diverge outwardly to facilitate winding of the lead cords 22, even though the winding drum unit may not be always held at right angles to the lead cords.

The outwardly extending portions 30a of the drum sections 30 which lie beyond the outer flanges 34 constitute hand hold portions and provide continuous and smooth drum end portions about which the hands can slide as the drum is being wound or unwound.

With a kite rigged in the manner shown, it is possible to control its flight directionally and to make it perform different maneuvers such as dips and loops by lengthening or shortening one of the lead cords 22 relative to the other. This can be done by either rotating one reel section or merely tilting the axis of the drum unit, depending upon the maneuver desired.

It has been found that bridle and lead cord arrangement such as shown and described will operate with complete success without a spreader bar between the bridles where they connect with the lead cords, thereby reducing the cost of material and the weight of the kite.

The manner of reinforcing the edges of the cover sheet 15 and also the manner of mounting the cover sheet on the frame provide a kite which is extremely strong and resistant to shocks.

The predetermined fixed angular relationship of the bridle cords relative to the cover sheet 15 is an important feature and the tie means or connecting means for the bridle cords make the device extremely easy to set up for use.

If a single bridle and lead cord are used, the bridle cord sections will be connected from a lower portion of the upright 11 to the upright and the cross-piece where they cross each other. For that purpose an aperture 36 may be provided in the upper central portion of the cover sheet 15.

It will, of course, be understood that various changes may be made in the form, details, arrangement and proportions of the various parts without departing from the scope of my invention.

What I claim is:

1. In a kite, a frame, a thin polygonal sheet of material approximately co-extensive with said frame, the corners of said sheet being reinforced, said reinforced corners having apertures there-through, said frame having portions lying adjacent the corners of said sheet, and an elastic connector between said sheet corners and adjacent portions of said frame.

2. The structure in claim 1 and said frame portions adjacent the corners of said sheet being extended outwardly beyond said corners, and said elastic connector being disposed between said sheet corners and outwardly extending frame portions.

FRED H. OHLAND.
